US0D1001061S

(12) **United States Design Patent** (10) **Patent No.:** **US D1,001,061 S**
(45) **Date of Patent:** **** Oct. 10, 2023**

(54) **RECHARGEABLE BATTERY**

(71) Applicant: **SHENZHEN ORIENTAL WILLING NEW ENERGY CO., LTD**, Shenzhen (CN)

(72) Inventor: **Kunli Wang**, Shenzhen (CN)

(73) Assignee: **SHENZHEN ORIENTAL WILLING NEW ENERGY CO., LTD**, Shenzhen (CN)

(**) Term: **15 Years**

(21) Appl. No.: **29/886,571**

(22) Filed: **Mar. 10, 2023**

(30) **Foreign Application Priority Data**

Mar. 1, 2023 (CN) 202330083548.7

(51) **LOC (14) Cl.** **13-02**

(52) **U.S. Cl.** ..... **USPC** **D13/103**

(58) **Field of Classification Search**

USPC D13/102-108, 110, 118, 119, 184, 199; D14/218, 223; D26/41, 49

CPC B29C 61/025; H01M 10/0431; H01M 50/107; H01M 50/179; H01M 50/213; H01M 50/598; H02J 7/0045

See application file for complete search history.

(57) **CLAIM**

The ornamental design for a rechargeable battery, as shown and described.

DESCRIPTION

FIG. 1 is a first perspective view of a rechargeable battery showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of another state of the rechargeable battery thereof.

The broken lines shown in the drawings depict portions of the rechargeable battery that form no part of the claimed design.

1 Claim, 9 Drawing Sheets
